PIEZOELECTRIC CRYSTAL LAPING APPARATUS

John M. Wolfskill, Erie, Pa.

Application April 14, 1947, Serial No. 741,347

6 Claims. (Cl. 51—131)

1

This invention relates to apparatus and method for grinding and lapping parts or pieces of material either irregular or regular in shape to relatively thin dimensions; more particularly this invention relates to the grinding and lapping of various shaped piezoelectric quartz crystals and electrodes therefor.

An object of this invention is to provide an apparatus for lapping piezoelectric crystals to extremely thin dimensions and close tolerances.

Another object of this invention is to provide an apparatus for lapping piezoelectric crystals to thicknesses of less than $\frac{1}{1000}$ of an inch and close tolerances.

Another object of this invention is to provide means whereby a crystal or other part or piece of material may be lapped to a thickness which is not dependent on the thickness of any carrier, holding, or driving means surrounding the crystal or other part or piece of material being lapped.

A further object of this invention is to provide an apparatus for lapping quartz crystals or similar pieces to thicknesses approaching the thickness of the abrasive particles employed.

It is another object of this invention to provide a means of accommodating all different shapes and sizes of quartz crystals or other parts to be lapped.

Still another object of this invention is to provide apparatus whereby parts may be lapped to difficult and exacting tolerances such as are required in the grinding and lapping of piezoelectric quartz crystals to high frequencies.

A further object of this invention is to provide means for lapping piezoelectric crystals and electrodes therefor or other devices to the required degree of surface finish encountered in high frequency operation.

It is still another object of this invention to provide a means of regulating the speed of lapping the surfaces of piezoelectric crystals and/or electrodes therefor by controlling the weight thereof.

Another object of this invention is to provide a lap for piezoelectric crystal blanks in which the piezoelectric crystal blanks are placed into holes formed in a circumferentially driven circular guide member that guides the piezoelectric crystal blanks over the lap.

Still another object of this invention is to provide a lap for piezoelectric crystal blanks in which the piezoelectric crystal blanks, with weights uniformly distributed thereover, are guided by a rigid circumferentially driven guide member over the lap.

Other and further objects of this invention will

2

be apparent to those skilled in the art to which it relates from the following specification, drawing, and claims.

In the prior art of lapping quartz crystals or other surfaces the piece being lapped is generally handled in one of two ways. Either the piece is cemented to a flat work holder by means of paraffin or similar wax or other pitch, either individually or in large quantities depending on the size of the pieces, and the entire work holder is moved about over another flat surface with an abrasive and vehicle between the aforesaid flat surface and surfaces being lapped.

Another method commonly used in the piezoelectric crystal lapping art is that in which the pieces being lapped are caused to move about between two flat surfaces by means of work holders which encircle the pieces being lapped, either closely or loosely enough to enable the pieces themselves to rotate in a space provided in the work holder.

These methods in the prior art are unduly limited insofar as the minimum thickness to which the piece or pieces may be lapped. The minimum thickness obtained by the method in which the pieces are fixed or cemented to the carrier is limited because of the distortion caused by the cementing or waxing medium on very thin pieces. The distortion takes place when the quartz crystal or other material is cemented to the work holder. The resulting lapped surfaces of the quartz or metal piece may be exceptionally flat prior to the removal thereof from the work holder but this surface may have been originally distorted in the cementing operation.

Upon removal of the quartz crystal or other material from the work holder after lapping distortions introduced therein in the course of the cementing operation are relieved and the quartz crystal or other material springs back to its naturally free condition so that the surface lapped onto it, either concave or convex, may or may not be regular. In addition, the thickness of the cementing medium between the pieces being lapped and the work holder may vary to such an extent that it is impossible to lap them to any specific thickness because the fastening medium varies and furthermore there is no telling what contour the work pieces have, until after removal thereof from the work holder.

The other method in the prior art has the definite disadvantage in that the thickness to which the quartz crystals or other material being lapped may be lapped is the thickness of the carrier or work holder which must be of a thickness and

strength to move the work pieces, that is, the quartz crystals or other material, between the laps without tearing, fracturing, or buckling. Regardless of what material such carriers or work holders are made, or regardless of the pressure on the lapping surface or between laps and work piece this disadvantage remains. There appears to be a practical limit to the thickness or thinness of the work holders of about .004" or .005" where the work holders tear, fracture, and/or buckle.

It is the purpose of this invention to disclose an apparatus for lapping piezoelectric crystals to extremely thin dimensions with the limits in minimum thickness fixed only by the precision to which the lapping plates are made, and to the maximum size of the abrasive grain used.

Briefly, this apparatus comprises a piezoelectric crystal blank guide that is rotated over a lap such that the guide makes several rotations for each rotation of the lap. The ratio of five to one or six to one has been used in this development but this can be varied over wide limits. The crystal blank guide is rotated by a pair of rollers engaging the periphery thereof in such a manner that the abrasive action on the lap remains consistent over its entire surface. One or more holes are drilled through the crystal blank guide and the crystal blanks are placed in these holes. The work pieces or crystal blanks themselves can be of any shape laterally and a freely floating cylinder is placed on top of each of the work pieces or piezoelectric crystals to provide pressure against the lap. The holes drilled in the crystal guide confine the work piece and the bottom ends of the freely floating cylinders press on the work pieces. The bottom surface of these cylinders may be flat to produce flat work piece or crystal surfaces or they can be made convex, for instance so that most of the pressure will be in the central area of the work piece and this will produce a concave surface on the work pieces or crystals, if it is desired. For instance, to lap a quartz crystal concave this method would be used. If it is desired to lap one face of the crystal convex, the end of the cylinder pressing against the crystal could be made concave in which case the pressure would be around the periphery of the crystal and this portion would be lapped down faster than the center area. In producing extremely flat surfaces the cylinder faces themselves must be flat so that the pressure is uniformly distributed over the crystal or work piece surfaces. Such a flat surface on the cylinder face is easily established by lapping the entire crystal blank guide with its complement of cylinders without the work pieces inserted. This can be carried on prior to loading of the crystal blank guide with piezoelectric crystal blanks.

Round as well as square crystals can be lapped in this apparatus. However, if a square or rectangular shaped crystal or work piece is lapped, the sideways or lateral pressure on the corners may become excessive if the square or rectangular crystals are positioned in the round holes of the crystal blank guide. If the crystal is extremely thin, the pressure may be sufficient to fracture the corners. In such instances, the crystal blank guide may be further modified either by using a square hole originally therethrough, which is difficult to machine, or by introducing a free cylinder with a square hole through it and in which a freely floating square or rectangular weight can be placed. In order to get around the difficulty of machining a square hole through a cylinder

the original round cylinder may be split into two parts or may even consist of three or four parts. If it is split the two similar cylinders can be milled in the center so as to form any desired shape internally to accommodate the square or rectangular work pieces.

Further details of this invention will be apparent to those skilled in the art to which it relates from the following specification, claims and drawing in which briefly:

Figure 1 is a side view of an embodiment of this apparatus;

Figure 2 is a fragmentary top view of Figure 1;

Figure 3 is a sectional view of the piezoelectric crystal guiding member taken along the line 3-3 of Figure 2; and

Figure 4 is a fragmentary view of a crystal guiding member adapted for lapping a plurality of crystals simultaneously, some of the crystals being round and some being rectangular.

Referring to Figure 1 of the drawing in detail reference numeral 10 designates the base plate supporting the piezoelectric crystal lapping apparatus and attached to this base plate are the upright members 11 that support the table 12. The shaft 13, the bottom end of which rests upon a thrust bearing 14 fitted into the base 10, is provided with a worm gear 15 keyed thereto. This worm gear 15 is driven by the worm wheel 16 that is attached to the shaft of the motor 17 resting on the aforesaid base plate 10. Gear 18 which forms part of the gear train including gears 18, 19, and 20 is keyed to the shaft 13. The lap wheel 21 having an integral extension 22 is spaced from the top of the table by the length of the extension 22 and is keyed to the shaft 13 by the pin 23. Roller 24 positioned above the lap wheel 21 is also keyed to the shaft 13 and this roller forms one of the peripheral driving elements for the circular piezoelectric crystal guiding member 25. Another roller 26 keyed to the shaft 27 to which is attached the gear 20, also engages the periphery of the piezoelectric crystal guiding member 25 and these two rollers 24 and 26 are spaced apart a distance smaller than the diameter of the piezoelectric crystal guiding member 25.

The roller 24 is rotated by the motor 17 through worm gear 15 and worm wheel 16 and the shaft 13 whereas the roller 26 is rotated by the motor 17 through the aforesaid worm gear and worm wheel, shaft 13 and the gear train consisting of the gears 18, 19, and 20 that rotate the shaft 27 to which the roller 26 is attached.

In this way the rollers 24 and 26 both rotate in the same direction and cause the circular piezoelectric crystal guiding member 25 to rotate over the top face of the lap 21 as this lap is itself rotated by shaft 13. The guide member 25 is made of smaller diameter than the distance between the rollers 24 and 26 so that the member 25 will be thrust against these rollers 24 and 26 as the lap 21 is rotated in the direction indicated by the arrow 28, but will not be permitted to pass between these rollers 24 and 26 because of its greater diameter.

The guide member 25 is provided with a hole 29 which may be positioned in the center or it may be displaced from the center thereof. A plurality of holes such as hole 29 may be provided in the guiding member 25 as will be described. Weight 30 fitting into the hole 29 is positioned therein and rests evenly upon the piezoelectric crystal blank 31 as shown in Figure 3. A coil spring 32 surrounding the stud 33

of the weight 30 and positioned between the weight 30 and the clamping strip 34 is employed for the purpose of providing additional pressure uniformly to the piezoelectric crystal blank. The clamping strip 34 is fastened to the grinding member 25 by the machine screws 35, and suitable slots 36 as shown in Figure 2 may be cut into the strip 34 so that this strip may be slightly rotated and released from the grip of the machine screws 36 when desired.

The abrasive with a suitable vehicle, such as, kerosene, oil, water, or the like, may be fed to the piezoelectric crystal blank 31 by placing some of the abrasive and vehicle into the hole 29 above the weight 30. This abrasive and vehicle will work down to the piezoelectric crystal blank between cylindrical surface of the weight 30 and the walls of the hole 29 during the lapping operation. Of course the abrasive and vehicle may also be placed on the top surface of the lap 21, and allowed to work to the piezoelectric crystal blank during rotation of the lap.

In Figure 4 is shown a fragmentary view of a piezoelectric crystal guide member 25a, corresponding to the guide member 25 shown in Figures 1, 2, and 3, having a plurality of holes 29a for receiving a plurality of piezoelectric crystal blanks simultaneously. In the form shown in Figure 4 a plate 34a having a plurality of ears 38 spaced around the periphery thereof, is employed for applying pressure to the weight members 30a position in the holes 29a. Each of these weight members is provided with a stem 33a which is surrounded by a spring corresponding to the spring 32 as shown in Figure 3 so that additional pressure may be provided to the weights when the plate 34a is assembled to the guide 25a. This plate 34a is attached to the guide member 25a by suitable machine screws 35a engaging the ears 38.

A portion of the plate 34a is shown cut away for the purpose of showing the cylindrical plugs 37 positioned in two of the holes 29a. These plugs 37 are split through the center and are provided with rectangular holes therethrough into which rectangular crystal blanks may be inserted whereby this apparatus may be adapted for lapping of rectangular piezoelectric crystals. In this case the weight fitting into the rectangular hole is also of rectangular configuration and is freely floating in the hole so as to press on the crystal blank uniformly over the face thereof, for the purpose of lapping a crystal blank of uniform thickness. Where it is desired to get convex crystal blanks the face of the weight is concave as pointed out above or if it is desired to obtain concave crystal blanks the face of the weight is convex as also is pointed out above.

While I have described certain embodiments of this invention in detail it is of course understood that modifications of this invention may be made without departing from the spirit and scope thereof and I do not desire to limit this invention to the exact embodiments described and illustrated except insofar as these are defined by the appended claims.

I claim:

1. Apparatus for lapping piezoelectric crystal blanks to a thinness corresponding substantially to the size of the abrasive particles used in the lapping process comprising a lap plate, means for rotating said lap plate, a rigid substantially circular piezoelectric-crystal-guiding member freely resting on said lap plate, said guiding member having a thickness equal to several times the

thickness of the crystal blank, said guiding member having a hole formed therein for receiving a piezoelectric crystal of thin wafer-like configuration, said hole having a diameter corresponding substantially to the diameter of said piezoelectric crystal, means for frictionally engaging the periphery of said guiding member for rotating said piezoelectric-crystal-guiding member over the lapping surface of said lap plate, and means fitting into said hole for uniformly pressing a surface of said piezoelectric crystal against said lap plate without distorting the shape of said piezoelectric crystal.

2. Apparatus for lapping piezoelectric crystal blanks to a thinness corresponding substantially to the size of the abrasive particles used in the lapping process comprising a lap plate, means for rotating said lap plate on its axis, a piezoelectric-crystal-guiding member freely resting on said lap, said guiding member having a hole formed therein for receiving a piezoelectric crystal of thin wafer-like configuration, said guiding member having a thickness equal to several times the thickness of the crystal blank, said hole having a diameter corresponding substantially to the diameter of said piezoelectric crystal, means for engaging the periphery of said piezoelectric-crystal-guiding member for rotating said member over the lapping surface of said lap plate, and means fitting into said hole for uniformly pressing a surface of said piezoelectric crystal against said lap plate without distorting the shape of said piezoelectric crystal.

3. Apparatus for lapping piezoelectric crystal blanks to a thinness corresponding substantially to the size of the abrasive particles used comprising a lap plate, means for rotating said lap plate, a piezoelectric crystal guiding member freely resting on said lap plate, said guiding member having a thickness equal to several times the thickness of the crystal blank, said guiding member having a hole formed therein for receiving a piezoelectric crystal of thin wafer-like configuration, said hole having a diameter corresponding substantially to the diameter of said piezoelectric crystal, means for frictionally engaging the periphery of said guiding member for rotating said piezoelectric crystal guiding member over the lapping surface of said lap plate, a weight fitting into said hole for uniformly pressing a surface of said piezoelectric crystal against said lap plate without distorting the shape of said piezoelectric crystal, and a spring member for pressing said weight against said piezoelectric crystal.

4. Apparatus for lapping piezoelectric crystal blanks to a thinness corresponding substantially to the size of the abrasive particles used comprising a lap plate, means for rotating said lap plate, a piezoelectric crystal guiding member freely resting on said lap plate, said guiding member having a plurality of holes formed therein for receiving a piezoelectric crystal of thin wafer-like configuration, said hole having a diameter corresponding substantially to the diameter of said piezoelectric crystal, means for frictionally engaging the periphery of said guiding member for rotating said piezoelectric crystal guiding member over the lapping surface of said lap plate, a weight fitting into said hole for uniformly pressing a surface of said piezoelectric crystal against said lap plate without distorting the shape of said piezoelectric crystal, a spring for pressing said weight against said piezoelectric crystal and a bar-shaped member for retaining said spring in place.

5: Apparatus for lapping piezoelectric crystal blanks to paper thin dimensions and close tolerances, comprising the combination of a lap, a rigid guide member freely resting on said lap, said guide member having a thickness equal to several times the thickness of the crystal blank, said rigid guide member having a hole formed therethrough for receiving a piezoelectric crystal blank, weight means at least partially positioned in said hole for uniformly pressing said piezoelectric crystal blank against said lap, means for rotating said lap and means for engaging the circumference of said rigid guide member and for rotating said rigid guide member and the piezoelectric crystal blank guided thereby over said rotated lap, the surface of the said weight means pressing the said piezoelectric crystal blank being of convex configuration so that said crystal blank is lapped to concave configuration.

6: Apparatus for lapping piezoelectric crystal blanks to paper thin dimensions and close tolerances, comprising the combination of a lap, a rigid guide member freely resting on said lap, said guide member having a thickness equal to several times the thickness of the crystal blank, said rigid guide member having a hole formed therethrough for receiving a piezoelectric crystal blank, weight means at least partially positioned in said hole for uniformly pressing said piezoelectric crystal blank against said lap, means for rotating said lap and means for engaging the

5 circumference of said rigid guide member and for rotating said rigid guide member and the piezoelectric crystal blank guided thereby over said rotated lap, the surface of the said weight means pressing the said piezoelectric crystal blank being of concave configuration so that said crystal blank is lapped to convex configuration.
